SHEET FEEDER

James R. Wood, Cleveland, Ohio, assignor to Harris-Seybold Company, Cleveland, Ohio, a corporation of Delaware

Application January 6, 1951, Serial No. 204,756

6 Claims. (Cl. 271—12)

This invention relates to improvements in sheet feeders of the type which are adapted to feed sheets either in a slow moving stream of overlapped sheets or rapidly in single file, generally termed single sheet feeding or sheet by sheet feeding.

One of the objects of the invention is the provision of driving mechanism which can be adjusted by the operator quickly and easily to enable him to shift from feed of one type to that of the other.

Another object is to facilitate preparation for printing by using sheet by sheet feeding while the necessary adjustments are being made, involving a minimum of spoilage of sheets, after which a shift to stream feeding may be effected.

Other objects and features of novelty will appear as I proceed with the description of those embodiments of the invention which, for the purposes of the present application, I have illustrated in the accompanying drawings, in which

Fig. 1 is a fragmental side elevational view illustrating a pile feeder embodying the invention and connected with a printing press, the impression cylinder only of which is shown.

Fig. 2 is a sectional detail view on a larger scale showing the drive from the press to the sheet separator and to the tape drive roller. The view may be considered as taken approximately on the line 2—2 of Fig. 1, although it shows a modified form of the invention.

Fig. 3 is an elevational view also on a large scale illustrating especially the mechanism for imparting non-uniform drive to the tape driving rollers for sheet by sheet feeding, and

Fig. 4 is a diagrammatic view showing the velocity of the conveyor tapes while running for sheet by sheet feeding or alternatively while running for stream feeding.

Referring first to Fig. 1 of the drawing, 10 indicates the frame of a rotary printing press in which is rotatably mounted in the usual manner an impression cylinder 11. 12 is a feed board which extends forward at a slight downward inclination to a point directly above cylinder 11, and 13 represents a set of front stops which are mounted and actuated to swing down to the operative position illustrated at the proper time in each printing cycle and to swing upwardly out of the way during the rest of the cycle. They are operated in a conventional manner, as for example by means of a cam, not illustrated, turning with cylinder 11.

Shaft 14 is geared to the shaft of cylinder 11 to turn at the same speed. It carries a sprocket wheel 15 over which an endless chain 16 runs to a second sprocket 17 mounted on the sheet feeder. The sheet separating and forwarding mechanism is driven in one to one relation with the rotation of sprocket 17 and consequently in the same relation with that of cylinder 11 and the cooperating cylinders of the printing press.

Portions of the side members of the feeder frame are shown at 18 and 19. In frame member 18 there is mounted a bushing 20. A shaft 21 is journaled in this

2

bushing so as to project somewhat beyond frame member 18, the other end of the shaft being journaled in the other frame member 19. On the outer side of frame member 18 a hub 22 is keyed to shaft 21. It is provided with an annular rabbet 23 which is of slightly less depth than the thickness of annular sprocket wheel 17 which fits within the rabbet and is angularly adjustable therein. A clamping plate 24 surrounds shaft 21 and overlaps sprocket wheel 17. A portion of the periphery of this plate is cut away as indicated at 25 to accommodate a pin 26 that is mounted in sprocket 17 and is adapted to bear against one or the other of the shoulders at the ends of the cutaway portion 25 of the clamping plate.

Clamping plate 24 is anchored in hub 22 by means of three bolts 27 upon the outer ends of which are nuts 28. When plate 24 is to be adjusted from the position illustrated in Fig. 3 to a position in which pin 26 abuts against the shoulder 29, nuts 28 are loosened, the plate 24 is turned to the new position and the nuts again tightened. To facilitate this operation the extremity of shaft 21 may be provided with parallel flat surfaces to receive a wrench so that the shaft, the hub 22 (and plate 24) may be turned relative to sprocket 17.

In the Fig. 1 form of the invention the sprocket 17 is 25 permanently attached to hub 22 instead of being adjustable relative thereto as just described and as shown in Figs. 2 and 3.

A second sprocket wheel 32 and a gear 33 are locked to hub 22 by the bolts 27. A chain 34 runs over sprocket 32 and over a sprocket 35 which is locked to a hub 36 that is keyed to a shaft 37. The chain may be maintained taut by means of an idler sprocket 31. By the means described 30 shaft 37 is caused to turn one revolution for each revolution of shaft 21 and consequently for each revolution of cylinder 11. Shaft 37 drives the sheet separating and 35 forwarding mechanism disposed above the rear of a pile 38 of sheets which are to be fed to the press, and by this mechanism a sheet is separated from the pile at each cycle of the press and started forward toward the press. This 40 separating and forwarding mechanism will be described very briefly since per se it forms no part of the present invention.

Shaft 37 carries a bevel gear indicated at 40 in Fig. 1 which meshes with a bevel gear 41 pinned to a short shaft 42. On the latter shaft there is a pinion 43 which meshes with a second pinion 44 that is keyed to a shaft 45 which extends from front to rear of the feeder. At its rear end it is connected by bevel gears 46 to a transverse shaft 47 upon which is fixed a cam 48 turning one to one with the press. A follower 49 on a bell crank 50 is actuated by the cam to reciprocate a rod 51 which swings an arm 52 pinned to a shaft 53 upon which are mounted one or more legs 54 carrying suckers 55 at their lower ends which serve to lift the rear edge of the 55 sheet. By the swinging motion of the legs 54 the top sheet may be pulled rearwardly a short distance to break it loose from the pile and then carried forward, preferably over one or more air blasts, until the forward edge enters the bight of the nipper or pull-out rolls. The forward speed of suckers 55 is preferably made equal to the surface speed of the pull-out rolls so that control of the sheet will be transferred smoothly from the suckers to the conveyor. After the sheet has been taken by the conveyor, the suction is cut off and the suckers decelerate to zero speed and then return to their sheet taking position. The pull-out rolls in the illustrated case comprise a tape driving roller 56 over which conveyor tapes 57 run and a series of wheels 58 disposed to bear upon the tapes or the sheets on the tapes and by their own weight or by suitable spring loading to press the sheets against the tapes and thus impart good traction. The upper runs of the tapes 57 of course overlie the feed board 12 and

70

at the forward end of the feed board they run over an idler roller 59.

Uniform drive to conveyor tapes.—For stream feeding the tapes 57 are caused to move at a constant relatively low speed. To this end a pinion 62 is keyed to shaft 21. It is adapted to mesh with a pinion 63 that is slidably keyed to the shaft 64 upon which the tape driving rollers 56 are mounted. Shaft 64 is parallel to shaft 21 and closely adjacent thereto and is suitably journaled in frame members 18 and 19. A second pinion 65 identical in size with pinion 62 is rotatably mounted on shaft 21 between bushing 20 and pinion 62. Pinion 63 may be caused to mesh with either of pinions 62 and 65 or it may occupy a position between those pinions and out of mesh with both of them, as illustrated in Fig. 2. The shifting of pinion 63 lengthwise of shaft 64 may be effected by any convenient means. In the illustrated case I employ a yoke 66 which engages a peripheral groove in the pinion and is attached to a shift rod 67 that may be moved lengthwise through a bushing 68 mounted in the frame member 18. The movement is effected by means of a manually turnable shaft 69 having a knurled knob 70 which may be turned approximately 90° in either direction from its neutral position. Shaft 69 at its inner end carries a disk 71 in which is anchored a pin 72 that is disposed between a pair of spaced plates 73 on rod 67. As will be apparent the turning of knob 70 a quarter turn in one direction from the neutral position of Fig. 2 will shift pinion 63 into mesh with pinion 65, while turning it a quarter turn in the opposite direction will shift it into mesh with pinion 62.

When pinions 62 and 63 are in mesh drive will be transmitted from chain 16 through sprocket 17 to shaft 21 and thence through the meshing pinions to shaft 64, which will cause the tapes 57 to travel at a constantly uniform low rate of speed.

Non-uniform drive to tapes for sheet by sheet feeding.—This drive embodies a bell crank lever indicated generally at 75 that is oscillatable about the axis of shaft 21. In this bell crank one of the arms is formed as a yoke having spaced sections 76 and 77 attached at their outer ends to a sleeve 78 and at their inner ends having hubs 79 and 80 which are journaled on the bushing 20 on opposite sides of a projecting part of the frame member 18. A short shaft 81 extends through sleeve 78. On one end it has a small gear 82 keyed thereto and meshing with gear 33. On its opposite end there is keyed a larger gear 83 which meshes with pinion 65. The train comprising gears 33, 82, 83 and pinion 65 obviously drives pinion 65 at a higher angular speed than shaft 21.

The other arm 85 of the bell crank carries at its extremity a nodde pin 86 through which is mounted to slide a rod 87. A compression spring 88 surrounds this rod between the nodde pin and a collar 89 fixed on the rod, the latter being pivotally anchored on the frame member 18 at 90. Also pivoted to arm 85 there is a link 91 which extends up to and is pivotally connected with one arm 92 of a lever that swings upon a pivot 93 carried by the frame. The other arm 94 of this lever carries a roller follower 95 which runs upon the periphery of a cam 96 that is locked to hub 36 on shaft 37. Conveniently this cam and the sprocket 35 are fastened to the hub by the same bolts 97. By the connections described, as the follower 95 rides out onto the high portion of the cam the bell crank 75 is swung in the clockwise direction, and as the spring 88 causes the follower to ride down onto the lower portions of the cam the bell crank is swung in the counterclockwise direction.

The oscillation of the bell crank and the resulting travel of the gears 82 and 83 over the gear 33 and pinion 65, part of the time to increase the up gearing through the gear train and part of the time to decrease it, provides a non-uniform rate of travel to the conveyor tapes, but the control of these oscillations by means of the cam permits the degree of slow-down and speed-up, and the

extent of each, to be selected for the best results. The diagram of Fig. 4 shows how the illustrated construction takes advantage of this fact. In this diagram the velocity of the tapes during one cycle of the press is shown at 100 for stream feeding, and the different velocities for sheet by sheet feeding are indicated at 101, 102 and 103 connected by diagonal lines indicating the increasing and decreasing speeds.

As indicated in the diagram the speed ratio between sheet by sheet feeding and stream feeding may be of the order of three and one-half to one. By means of the cam however this non-uniform speed is reduced during the period marked A to the same speed as that at which the tapes run continuously for stream feeding, which is 15 the speed that corresponds to the forward travel of suckers 55. To make up for this lower than basic speed during the period marked C the cam provides a greater than basic speed for the comparatively extended period B. The timing is such that during the low speed period A 20 when the forward edge of one sheet is presented to the bight between pull-out rolls 56 and 58 the forward edge of the preceding sheet is being presented to the front stops 13.

The mechanism for separating the sheets and forwarding them off the pile moves always at the same rate and the conveyor at the time it takes a sheet moves also at the same rate and therefore cooperates properly with the sheet feeding means regardless of which type of feed is being employed. Also the slow travel of the tapes when a sheet is presented to the front stops in both types of feed prevents bouncing back of the sheets or crumpling of their front edges.

In the Fig. 1 form of the invention the distance between the pull-out rolls 56, 58 and the front stops 13 is an exact multiple of the spacing of the front edges of the sheets in the stream. Also in this form of the invention the sprocket 17 is not adjustable as the sheets fed by either stream feeding or sheet by sheet feeding engage the front stops at the same instant in the press cycle. When the 40 mechanism is operated for sheet by sheet feeding the front edge of one sheet enters the pull-out rolls at the same time that the front edge of the preceding sheet engages the front stops, and this is at the time that the velocity of the tapes is at the station A of the Fig. 4 diagram.

When however the distance between the pull-out rolls and the front stops is not a multiple of the spacing of the front edges of the sheets of the stream it is necessary in order to stream feed to change the timing of the sheet separator and forwarder so as to cause the sheets to engage the front stops at the same instant in the press cycle as that at which the sheets engage the front stops while sheet by sheet feeding. It is for this reason that the plate 24 must be placed in the Fig. 3 position while stream feeding. For sheet by sheet feeding the plate 24 must be swung counterclockwise from the position of Fig. 3 until the pin 26 strikes the shoulder 29 upon the clamping plate 24.

Obviously the movement of yoke 66 by the hand knob 70 to cause pinion 63 to mesh with one or the other of pinions 62 and 65 may be effected almost instantly, and this is all that is necessary to change from one type of feed to the other provided that the distance between pull-out rolls 56, 58 and front stops 13 is a multiple of the spacing of the front edges of sheets making up a stream. In case this dimension is not built into the machine then it becomes necessary to shift the sprocket 17 from one position to the other as previously described. When the machine is being operated as a stream feeder the bell crank 75 will oscillate back and forth and the gears 33, 82 and 83 will turn, but inasmuch as pinion 65 is not then in mesh with pinion 63 the oscillation of the bell crank will have no effect.

Having thus described my invention, I claim:

1. In a sheet feeder for printing presses or other sheet

handling machines, a feed board, sheet separating means having a forwarding action, front stops, conveyor means for taking the sheets from said separating means and moving them forwardly over said feed board either singly or in constant speed stream feed relation, and a drive for said conveyor means selectively operable at constant stream feed speed or at non-uniform speed between stream feed speed and higher speeds, the stream feed speed and the non-uniform speed at the time each sheet is taken by the conveyor being the same and corresponding with the forwarding action of said sheet separating means.

2. In mechanism of the character described, a tape roll shaft, a drive shaft, a pinion loose on said drive shaft, a second pinion keyed to said drive shaft, a yoke oscillatably mounted on said drive shaft, a gear train comprising said loose pinion, a gear on said drive shaft and a pair of gears on said yoke, means for oscillating said yoke, and shift means for operatively connecting either one of said pinions to said tape roll shaft, whereby the latter may be driven at constant stream feed speed or at non-uniform speed for single sheet feed.

3. Mechanism as defined in claim 2, comprising a cam driven at the same angular speed as said drive shaft and a cam follower operatively associated with said yoke for oscillating the same, the oscillation of said yoke by said cam being such as to impart rotation to said loose pinion during a portion of each cycle at the same angular speed as that of said drive shaft.

4. In mechanism for feeding sheets from a pile selectively in a stream or singly, sheet separating means having a sheet forwarding action operated at constant speed, a feed board, means for conveying sheets over said feed board, pull-out rolls cooperating with said conveying means at the rear end thereof, and drive means for said conveying means adjustable to a constant low speed for stream feeding or to a non-uniform speed for sheet by sheet feeding, said constant low speed corresponding to the speed of operation of said sheet separating means, said non-uniform speed drive operating at said low speed at the time a sheet is taken by said conveying means from said separating means and at higher speeds throughout the remainder of the cycle.

5. In mechanism for feeding sheets from a pile selectively in a stream or singly, sheet separating means having a sheet forwarding action operated at constant speed, a feed board, front stops at the forward end of said feed board, means for conveying sheets over said feed board, pull-out rolls cooperating with said conveying means at the rear end thereof, and drive means for said conveying means and pull-out rolls adjustable to a constant low speed for stream feeding or to a non-uniform speed for sheet by sheet feeding, said constant low speed corresponding to the speed of operation of said sheet separating means, said non-uniform speed drive operating at said low speed at the time a sheet is taken by said conveying means from said separating means and at the time said conveying means advances the preceding sheet into engagement with said front stops.

6. In mechanism for feeding sheets from a pile selectively in a stream or sheet by sheet, sheet separating means having a sheet forwarding action operated at constant speed, a feed board, front stops at the forward end of said feed board, means for conveying sheets over said feed board, pull-out rolls cooperating with said conveying means at the rear end of said feed board, drive means for said conveying means and pull-out rolls adjustable to a constant low speed for stream feeding or to a non-uniform speed for sheet by sheet feeding, said constant low speed corresponding to the speed of operation of said sheet separating means, said non-uniform speed drive operating at said low speed at the time the forward edge of a sheet engages said pull-out rolls and at the time the forward edge of another sheet engages said front stops, the distance between said pull-out rolls and said front stops being a multiple of the spacing of the front edges of the sheets in the stream.
